United States Patent Office

Des. 188,134
Patented June 7, 1960

188,134

BOTTLE

Robert G. Neubauer, Bridgeport, Conn., assignor to General Foods Corporation, White Plains, N.Y., a corporation of Delaware

Filed Nov. 10, 1958, Ser. No. 53,328

Term of patent 14 years

(Cl. D58—8)

FIG. 1

The side not shown is the same as the side shown.
I claim:

The ornamental design for a bottle, as shown and described.
